Des. 222,283
Patented Oct. 12, 1971

222,283

CHILD'S COASTER VEHICLE

Robert G. Reeves, 106 Kinderway Ave.,
Charlotte, N.C. 28214

Filed July 15, 1970, Ser. No. 23,965

Term of patent 14 years

Int. Cl. D21—01

U.S. Cl. D34—15

FIG. 1 is a perspective view of a child's coaster vehicle showing my new design;

FIG. 2 is a front elevational view thereof;

FIG. 3 is an opposite side elevational view thereof; and

FIG. 4 is a top plan view thereof.

I claim:

The ornamental design for a child's coaster vehicle, as shown.
